UNITED STATES PATENT OFFICE.

ANDREW J. BAKER, OF GOLDEN, COLORADO.

PLANETARIUM.

1,286,909.

Specification of Letters Patent.

Patented Dec. 10, 1918.

Application filed March 11, 1918. Serial No. 221,766.

To all whom it may concern:

Be it known that I, ANDREW J. BAKER, a citizen of the United States, residing at Golden, in the county of Jefferson and State 5 of Colorado, have invented certain new and useful Improvements in Planetariums; and I do hereby declare the following to be a full, clear, and exact description of the invention, such as will enable others skilled in 10 the art to which it appertains to make and use the same.

This invention relates to improvements in that type of astronomical machines, more generally termed planetariums, the globular 15 elements of which, when actuated, are designed to imitate the relative natural motions, positions, and orbits of the members of the solar system which they represent.

The primary essentials of the present improvements more particularly relate to the 20 terrestrial group symbols of the planets Venus, Mars, and the earth in conjunction with the moon, and the proper control of their independent and conjoint movements 25 and phases, in their orbital revolution of the sun. I shall, therefore, illustrate and describe my invention with particular reference thereto, but it will be obvious that elements representing other planets may be included in association therewith, if desired.

From the science of astronomy itself, the obliquity of these planets to the ecliptic is well understood, and that they cut the ecliptic in ascending and decending nodes. 30 Also their relative sizes, distances, orbits, and speed of travel are reasonably well established, so that I shall avoid reference to them as far as possible in the following description, excepting where necessary to 35 bring out the essential features of my invention.

However, I have made these prefacing remarks for the purpose of showing that in a machine of this character (designed more 40 for educational purposes than for strictly scientific demonstrations) actual proportional precisions in these respects are not so materially essential (provided they are reasonably proportionate) as that the mechan-

ism so properly controls the motion of the 50 symbol bodies as to cause them to move as they would do in nature.

With the foregoing statements, it will be understood that the general objects of my invention are to simplify and perfect the 55 accuracy of such types of machines, and as the specific objects and advantages of my particular improvements will be fully apparent, as incidental to the following disclosure, it would only be unnecessary repetition to initially state them more fully or in detail.

To more clearly understand the complete invention, however, and its method of operation, reference will now be had to the accompanying drawings, illustrating a practical embodiment of the same, in which drawings like reference characters designate the same parts in the several views, of which—

Fig. 1, is a diagrammatic assembly view of my improved educational apparatus, partly in vertical section and partly in side elevation, the base or supporting standard being broken away for convenience of illustration.

Fig. 2, is a detail central sectional view through the earth globe, taken in the plane of Fig. 1, and showing its axis shaft, with associated means for rotating the globe 80 therearound.

Fig. 3, is a detail horizontal sectional view through the moon globe supporting arm, the inner annulus element and disk support therefor (encompassing the hollow driving 85 shaft of the earth globe) being shown in top plan.

Fig. 4, is a cross-sectional view through the supporting upright of a novel form of indicator base support, looking down upon 90 the latter, and

Fig. 5, is a vertical sectional view, taken along the line 5—5 of Fig. 4.

1 designates a supporting base, provided on its top face with a circular depression 95 or recess 2, in which is adapted to be rotatably seated a circular disk 3, having a pair of diametrically opposed exposure openings

4, and which disk forms the base of or is fixedly mounted to the lower end of a rotatable hollow standard post 5, preferably formed with a hand gripping surface for 5 rotating same, although obviously other means of rotating same might be employed in practice if desired.

The functioning of this apertured disk relatively to said recessed base will be hereinafter more fully referred to.

In the drawings, the standard post 5 is shown hollow by the simple expedient of a longitudinal bore 6, through which there is extended a vertically disposed rod 7, fixedly 15 secured against rotation in any suitable way, conveniently shown as by means of the abutment element 8 and nut 9, securing the lower screwthreaded end to the supporting base 1. Around this rod 7, as an axis, the 20 standard post 5 and its disk 4 rotate when actuated.

The rod 7 extends upwardly beyond the top of the standard post 5, somewhat after the fashion of a double crank shaft, providing a U-shaped horizontal projection or arm 10, functioning as an offset or eccentrically disposed vertical bearing pin, thence projecting upwardly again, as at 11, in axial line with the lower portion 7, the 30 upper portion 11 serving as a support for a sun globe S, which is correspondingly superposed in fixed position.

The upper end of the post 5 is suitably cut-away or recessed out to provide for the mounting of certain gear elements. Just below its top, it is shaped as a circular eccentrically disposed cam element 12, encompassed by an apertured crown gear wheel 13, the bottom face of which latter is rotatably seated on the recessed post itself, while at the extreme top of said post, loosely seated relatively thereto, is mounted an oppositely disposed non-rotatable crown gear wheel 14, fixedly secured to the rod 7, and 40 interposed between the opposed teeth of these fixed and rotatable gear elements, to roll in mesh therearound, is an idler spur roller gear 15, suitably carried by a swinging arm hereinafter referred to.

Somewhat similarly, a fixed crown gear wheel 16 is secured to the portion 11 of the rod 7, immediately above the horizontal U-shaped arm 10, while spaced upwardly therefrom is an oppositely disposed rotatable crown gear wheel 17, carried by a short sleeve 18, loosely encircling the rod end 11, and interposed between these two gear elements, to roll in mesh therearound, is an idler spur roller gear 19, mounted and 55 functioning substantially in the manner of the roller gear 15.

20 designates a fixed crown gear mounted on the offset bearing pin or vertical arm of the U-shaped projection 10, and all of these

gear elements and mountings, mentioned in 65 the last two preceding paragraphs, will be clearly apparent from Fig. 1.

21 is a rod extending from the short sleeve 18 to support the Venus globe V, while 22 is a similar though much longer rod, extending from the eccentrically rotated crown gear wheel 13 to support the globe Ms representing the planet Mars. Naturally the rod 22 will be much longer than the 70 radius vector arm support (hereinafter referred to) for the earth and the moon globes, E and M respectively, for Mars being a superior planet, its orbit encompasses that of the earth's orbit.

Technically speaking the orbit of Mars is 80 decidedly elliptical, which has been represented by its eccentric mounting, and the Venus globe should also be mounted to travel in an eccentric orbit relatively to the sun, while both of the globes V and Ms 85 should be inclined at the proper angles of obliquity to the ecliptic; but these details are not so important, from an illustrative teaching viewpoint, as are the varying 90 phases and changes of position in the correlative movements of the moon and the earth globes and in their conjoint revolution or swing around the sun globe.

As four of the most salient features of my 95 improvements are aimed at the more accurate imitative functioning of these heavenly bodies, before specifically describing the actuating mechanism therefor, it may not be amiss to first emphasize that my objects with relation thereto are (1) to cause the 100 almost imperceptible bodily reciprocation of the earth globe E, toward and away from the sun globe S, along the radius vector line with the latter, and carrying the moon globe with it, while both are still performing their independent functions—which is the natural motion; (2) to cause the proper 105 actual approach and recession of the moon globe M relative to the earth globe E in its orbit therearound—both of the foregoing 110 as contradistinguished to machines mounting the earth globe on the end of a crank arm, whereby the earth globe swings in an orbit around the crank arm pivotal axis, which is manifestly erroneous, but which 115 deceptively appears correct to the student; (3) the provision of means for maintaining a constant band indicator of the line of semi-spherical illumination of the earth globe from the direct radiations of the sun; 120 and (4) the provision of a semi-globular illuminant shell, or its equivalent, revolvably encompassing the moon globe M, for indicating the phases of the moon, while at the same time maintaining substantially the 125 same surface of the moon globe toward the earth globe E as occurs in nature.

In the accomplishment of these aims, 23

designates a suitably formed swinging arm support, which I have termed a "radius vector arm" as it functions substantially in the manner of the radius vector of nature, 5 or the intangible line, varying in length, between the sun as the center of attraction and the earth's orbit.

In the drawings, this radius vector arm is shown as comprising a metallic elongated 10 housing, the top and bottom walls of the inner end of which are suitably apertured to pivotally surround the fixed rod end sections 7 and 11. It also freely encompasses the U-shaped offset bearing element 10, and 15 is fixedly mounted on the top of the standard post 5, so as to swing around therewith as the latter is rotated.

The outer top wall of this housing 23 is provided with a longitudinal slot 24 (Figs. 20 1 and 3) and reciprocatingly mounted therein, below said slot, is the earth and the moon globes' main supporting base, which will also be referred to as a "sliding base support."

25 In the drawings, this reciprocating support is illustrated as a box or casing 25, provided with a hollow post or sleeve 26, projecting upwardly through said slot 24 and adapted to ride longitudinally thereof.

30 As shown, it is suspended at one end by an extensible gate closure 27 for said slot, while its other end is partly supported by an actuating shaft, hereinafter referred to, although it might more properly be mounted 35 on roller bearings or guideways, as will be quite obvious.

28 designates a short stud bearing block 40 interiorly mounted on the bottom of said casing 25 and in line with said sleeve 26. 40 This bearing block is bored vertically to rotatably receive the lower end of the shaft 29, which passes upwardly through and beyond the top of said sleeve 26, where it terminates in an angular arm 30 of approximately 45 $23\frac{1}{2}$ ° to what would be the equatorial plane, and serves as the axis of the earth globe.

On the top of the bearing block 28 is rotatably seated a combined crown and spur 50 gear wheel element 31—32, fixed to the shaft 29, and being of different diameters.

33 is a hollow earth globe rotating shaft 55 enveloping the shaft 29, and at its lower end carrying a pinion 34 rotatably bearing on said spur gear element 32.

35 designates a combined spur gear and pinion element, dependingly supported from the top of the casing 25, and respectively meshing with said pinion 34 and spur gear 60 element 32, for differentially rotating said hollow shaft 33 at a greater speed than said axis shaft 29. Technically this differential speed should be such that the shaft 33 would rotate 365 times while the shaft 29 was rotat-

ing once, representing the daily rotation of 65 the earth on its own axis as compared to its bodily annual revolution around the sun. However, in a machine of this character it is manifest that this exact ratio need not be maintained.

The main actuating means for these several elements consists of a drive shaft 36, 70 extending longitudinally within said housing 23, being suitably journaled at its inner end, to prevent longitudinal displacement, 75 in a bushing 37, loosely embracing the vertical arm of said U-shaped offset 10, while the outer end passes through an aperture in the end wall of the casing 25, and is rotatably mounted in the bearing block 28. 37^a 80 are simply abutment disks fixed to the shaft 36, on opposite sides of the apertured wall of the casing 25, providing a rotatable connection between the shaft and casing.

The inner end of the shaft 36 is provided 85 with a pinion 38 meshing with the fixed crown gear 20, while the outer end is similarly provided with a pinion 39 meshing with the rotary crown gear element 31. The general functioning of all of these gear elements will more fully appear later, with reference to the operation of the whole machine.

Securely seated on top of the sleeve 26 is an inclined disk or flat table-like support 90 40, eccentrically mounted relatively to said sleeve, and apertured to permit of the projection of the hollow shaft 33 above the same. The bottom face of this disk 40 provides a fixed crown gear element 41, also eccentrically disposed, while on the top face thereof is freely and revolvably seated an internal gear wheel 42, held in eccentric position by the conjoint action of the spacing idler pinions 43 (Fig. 3) associated with a 100 pinion 44, carried by the upper end of the hollow shaft 33.

This element 42 is in reality an internally toothed annulus forming the inner terminal end of the moon globe supporting arm 45, 110 which latter is shown as a housing, at the outer end of which the axis shaft 46 of the moon globe is rigidly mounted at an angle to cause the moon globe M to revolve around the earth in an orbital plane of proper 115 obliquity to the ecliptic, approximately 5° 9'. While it is understood that the moon itself also rotates on its own axis, for illustrative educational purposes I prefer to maintain it fixed against rotation, so as to 120 always keep substantially the same surface to the earth globe as occurs in nature; but in substitution I provide independent means aimed to more accurately illustrate the moon's phases, and which I have termed an 125 illuminant moon phase indicator.

This moon phase indicator, comprises a revoluble semi-globular shell 47, of a bright

or illuminant color to indicate the shining of the sun thereon, which always covers that half of the moon globe disposed toward the sun globe. It is mounted on a hollow shaft 5 48, enveloping the moon axis shaft 46, and at its lower end, within the casing arm 45, it is provided with a crown gear wheel 49 meshing with a pinion 50 on the outer end of a driving shaft 51, suitably suspended 10 from said arm 45, while at its inner end the shaft 51 carries a larger spur pinion 52, meshing with the fixed crown gear element 41.

Referring now more particularly to Fig. 15 2 (in addition to Fig. 1) the upper end of the hollow shaft 33 is countersunk with a conical female series of gearing teeth 53, while the earth globe E is carried by a hub element 54, bored to permit of the free 20 passage of the axis 30 therethrough, and having a male conical series of teeth 55, the two sets of teeth being adapted to be partly maintained in mesh, as will be apparent, to rotate the earth globe around its own axis 25 30, at whatever position or direction that axis may be inclined in the earth globe's orbit around the sun globe.

Also as seen more clearly from Fig. 2, the hub element 54, at the end which carries 30 the earth globe, terminates in a pintle 56 for supporting a loose collar 57, which in turn carries a short arm 58, supporting the lower end of a band 59, encircling the earth globe to divide the same into two parts, 35 representing the constant line of illumination. The upper portion of this encircling band 59 is pivotally connected to a short curved extension 60, projecting from the top of a sleeve 61, which latter provides an 40 upper bearing for the earth globe, and which also projects inwardly of the globe to receive the upper end of the angular axis arm 30.

This sleeve 61 has the longitudinal slots 45 62 therethrough, in which is disposed a cross pin 63, passed through the arm 30, so that during the swing of the axis arm 30, the band is correspondingly moved with it.

It will be obvious, therefore, that the 50 whole arrangement permits of the free rotation of the earth globe on its own axis (daily) as well as permitting its axis 30 to gradually vary its angular position (annually) without disturbing the vertical 55 position of the "line of illumination" band, which remains constant relatively to dividing the earth globe at all times into two equal parts.

64 designates an abutment member fixed 60 to the axis arm 30, between which and the earth globe hub is disposed a coil spring 65. Obviously this will normally hold the earth globe down in operative position, with the gearing teeth 53 and 55 in mesh. Also

a coil spring 66 encircles the sleeve 61, engaging the cross pin 63 at one end and a flanged portion of the sleeve at the other end.

If for any reason, which not infrequently occurs in teaching, it is desired to turn the 70 earth globe around on its axis, regardless of its position in the zodiac, it is only necessary to slide the earth globe and its hub upwardly, against the tension of the springs 65 and 66, when the teeth 53 and 55 will become disengaged, and the whole may be rotated.

Of course, in such instances, the pin 63 of the axis arm will ride down its retaining slots in the sleeve 61.

80

The top recess 2, of the supporting base 1, is provided with an indicator surface representing the seasons of the year, the months, and the signs of the zodiac. These appear on the surface in concentric circles, 85 and are divided off radially into twelve sectors.

Around the inner circle, one of the twelve months appears in each sector, in sequential order, while around the outer circle, the 90 months one-half year distant appear in the same sectors. This arrangement is reversed on the diametrically opposite sector, that is to say the month that appears on the inner circle of the opposite sector now appears on the outer circle, and vice versa.

Intermediate of the inner and outer month circles, each sector also contains its proper sign of the zodiac, while the circle of the seasons is also disposed intermediately of 100 the month circles, and naturally the representation of the seasons spans or overlaps the monthly sectors.

As initially stated, a disk 3, at the lower end of the post 5, is rotatably seated in the recess 2, and conceals said indicator surface, excepting as to its sector exposure openings 4. Each of these exposure openings, in turn, is provided with an obscuring rim, either at its outer or its inner end, the one being adapted to cover the outer circle while the other covers the inner circle of months. These are respectively designated at 4^a and 4^b, and the radius vector arm 23 is so supported, on top of the rotatable post 5, that it projects outwardly in radial alinement above the exposure sector having the obscuring rim 4^a, for instance, and we will assume that it is the one selected primarily to indicate the seasons and months of the 115 northern hemisphere.

It will be obvious, therefore, that as the radius vector arm is swung around the sun globe, as will presently appear, the same months will be exposed for both the northern and southern hemispheres, as well as the proper signs of the zodiac under which the earth and sun globes are then supposed 125

to be situate relatively to each other. Contrariwise, however, opposite seasons will be indicated, which, as understood in nature, depend upon the inclination of the earth's axis toward or away from the sun, to more or less expose the north or south poles of the former to the direct rays of the latter, all of which is highly instructive to the student, and an almost inseparable feature of my improved planetarium, when viewed as a complete educational machine, in conjunction with its other manifest uses.

Operation.

- 15 In view of the foregoing complete description, the operation of the whole machine will be fairly apparent, but may be more connectedly described as follows:—
 When the supporting post 5 is rotated, the exposure disk 3 will function, in association with the indicator surface, as just described. At the same time, the radius vector arm 23 will be swung around with it, and in doing so the idler spur gear rollers 15 and 19 meshing, respectively, with the fixed crown gear elements 14 and 16 and with the rotatable crown gear wheels 13 and 17, will cause the latter to rotate at proportionate speeds, and swing the Mars and Venus globes around their orbits, through their supporting arms 22 and 21, the Mars globe traveling in an eccentric path, owing to the cam element 12, pivotally encompassed by the crown gear wheel 13.
- 25 35 Also the pinion 38, meshing with the fixed crown gear wheel 20, will rotate the shaft 36 and, through its pinion 39, the crown-spur gear element 31—32, fixed to the axis shaft 29, thereby swinging the globe axis arm 30 completely around, in an inverted conical path, from an inclination of $23\frac{1}{2}^\circ$ to a vertical line with the ecliptic to a reverse position at an inclination of $23\frac{1}{2}^\circ$ on the opposite sides of said line and then back again to initial position, during its cycle (annually) around the sun globe, thus providing for the reverse tilting of the earth's poles, regulating the seasons as in nature. At the same time, through the differential gearing elements 35, the pinion 34 is rotated and with it the hollow earth globe shaft 33, the upper end of which rotates the earth globe itself on its own axis arm 30 (daily) by means of the supporting hub 54 and interposed meshing teeth 53—55.
- 40 45 55 Dealing now with the moon globe, through the driven pinion 44, on the hollow shaft 33, meshing with the internal gear element or toothed annulus 42, the moon globe supporting arm 45 is swung around the earth globe in its sidereal monthly orbit, and during this cycle the moon globe, owing to the eccentric mounting of the annulus 42, is actually caused to approach the earth globe

in "perigee" and recede therefrom into "apogee" as in nature, as distinguished from machines heretofore mentioned, where the earth globe is mounted on the end of a crank arm, which together with the tilting of the earth globe, in that unwarranted orbit, causes the latter to approach and recede from the moon globe—deceptively incorrect. As before stated, and as seen from the drawings, the moon globe is mounted to travel in an orbital plane at proper obliquity to the ecliptic, substantially $5^\circ 9'$, causing its ascension and declination motions.

50 55 60 65 70 75 80 85 90 95 100 105 110 115 120 Also I prefer to mount the moon globe fixed to its axis support, representing its phases by the semi-globular "illuminant phase indicator" 47. This element is operated by its hollow supporting shaft 48, crown gear wheel 49, pinion 50, shaft 51, and larger spur pinion 52, which latter rolls around the fixed crown gear element 41, eccentrically mounted in correlation to said toothed annulus 42, the gearing ratio being such that the phase indicator always faces the sun globe, while the same appearing surface of the moon globe opposes the earth globe at all times. This distinguishes from a rotatable moon globe, painted bright on one-half of its surface to indicate the moon's phases, which bright portion truly faces the sun globe, but both bright and dark surfaces successively oppose the earth globe in the moon globe's orbit. Of course, in nature, the moon does rotate on its own imaginary axis, but not being fixed in space, other controlling forces keep substantially the same surface toward the earth. In a machine, however, where the real tangible axis is mechanically supported, a rotatable moon globe would necessarily present its whole surface to the earth globe in its orbit. Hence, for teaching purposes, I prefer to support the moon globe with its independently operating phase indicator as stated, functioning to more accurately illustrate the principle involved.

110 115 120 Finally, from the position of the disk 3, in the drawings the earth globe is being swung around to the right, from its position in "aphelion," and is now moving inwardly of the slot 24 as it approaches its "perihelion" position, being for the time traveling under the zodiac sign of "Aries," with the season for the northern hemisphere being at the beginning of autumn, while that of the southern hemisphere is indicated as early spring.

125 These movements in nature are a bodily motion along the radius vector line between the sun and the earth's elliptical orbit, and in my improved machine I have aimed to imitate this as closely as possible by the employment of the reciprocating element 25, providing a combined sliding support for

both the earth and moon globes, adapted to move back and forth along the radius vector arm 23, with almost imperceptible motion, during the orbit around the sun 5 globe.

As the radius vector arm 23, therefore, is swung around the sun globe, it is obvious that the shaft 36, in addition to imparting the individual motions of the earth and 10 moon globes, relatively to each other, will also slide the reciprocating element 25 along what would be the equivalent of the radius vector line, owing to the fact that the inner end of this shaft 36 is connected to the bushing 37, as a rotatable bearing around the 15 crank-like pin element 10, offset or eccentric to the rod 7-11 representing the sun globe's axis.

Thus is this movement of the earth globe 20 properly attained while the moon globe, being also indirectly supported by the same reciprocating element 25, will inherently follow the earth globe as its satellite symbol.

Having thus fully disclosed my invention, 25 it will be understood that I do not limit myself to all of the specific details as illustrated and described, excepting as come within the purview of the ensuing claims, when construed and interpreted in the 30 light of the specification, contemplating a fair range of equivalents.

What I do claim as new and patentable, is:—

1. In a planetarium, the combination with 35 a sun globe and a support therefor having an offset bearing element, of a radius vector arm mounted to swing therearound; a reciprocating support operative radially of the outer end of said vector arm; an earth 40 globe and a moon globe bodily carried by said reciprocating support; actuating means for said earth globe and said moon globe; a rotary sleeve pivotally encompassing said offset bearing; a main drive shaft rotatably 45 connected at its inner and outer ends, respectively, to said pivotal sleeve and said reciprocating support; means operatively connecting said drive shaft with said independent actuating means for said earth and 50 moon globes; and means for rotating said drive shaft by the swing of said vector arm, substantially as described.

2. In a planetarium, the combination with 55 a base support, having a circular recess in the top face thereof provided with an indicator surface, substantially as set forth; of a rotatable standard, carrying a circular disk at the bottom thereof rotatably seated in said recess, and provided with diametrically opposed exposure openings, functioning 60 as set forth; a radial arm fixedly secured at its inner end to said standard, and adapted to swing around therewith; a sun globe mounted above said radial arm in line with 65 said standard; an earth globe rotatably

mounted toward the outer end of said radial arm; a moon globe mounted to revolve around said earth globe; and means for rotating said earth globe and revolving said moon globe therearound, upon the rotation 70 of said standard and the swing of said radial arm around said sun globe, substantially as described.

3. In a planetarium, the combination with 75 a sun globe and a support therefor, of a radial arm mounted to swing therearound; a vertical shaft rotatably mounted toward the outer end of said radial arm and terminating in an upper angular swinging axis arm; a hollow shaft rotatably encompassing said 80 vertical shaft; an earth globe rotatably mounted on said axis arm; actuating means between said hollow shaft and said earth globe for rotating said earth globe on its axis arm; a "line of illumination" indicator 85 band mounted to encircle said earth globe and be maintained in a constant vertical position, regardless of the position of inclination of said angular axis arm or of the rotation of said earth globe; and means for rotating said vertical shaft and its encompassing hollow shaft, upon the swing of said 90 radial arm around said sun globe, substantially as described.

4. In a planetarium, the combination with 95 a base support, of a rod projecting upwardly therefrom and a sun globe mounted thereon; a standard post rotatably encircling the lower portion of said rod and mounted on said base support; a gear wheel mounted on 100 said post and eccentrically rotatable around said rod; a second rotatable gear wheel mounted adjacently below said sun globe; a radial arm fixedly secured at its inner end to said post intermediate of said rotatable 105 gear wheels; fixed gear elements on said rod spaced from said rotatable gear wheels; arms carried by said upper and lower rotatable gear wheels, respectively supporting a Venus and a Mars globe; an earth globe 110 rotatably supported at the outer end of said radial arm, intermediate of the orbits of said Venus and Mars globes; a moon globe mounted to revolve around said earth globe; means for rotating said earth globe and revolving said moon globe therearound, upon the swing of said radial arm; and idler spur rollers, carried by said radial arm, in rolling mesh with said fixed gear elements and 115 rotatable gear wheels for rotating the latter, substantially as described.

5. In a planetarium, the combination with 120 a sun globe and a support therefor, of a radial arm mounted to swing therearound; a vertical rotary shaft at the outer end of 125 said radial arm, and terminating in an upper angularly swinging axis arm; a rotary hollow shaft encompassing said vertical shaft; a rotary earth globe on said axis arm; actuating means between said hollow 130

shaft and earth globe, for rotating the latter; a moon globe arm mounted to swing eccentrically of said vertical shaft; a moon globe carried thereby, and adapted to revolve around said earth globe in an eccentric orbit; gearing elements between said moon globe arm and said hollow shaft, for swinging the former; and means for rotating said vertical shaft and its encompassing hollow 70 shaft, upon the swing of said radial arm around said sun globe, substantially as described.

6. In a planetarium, the combination with a sun globe and a support therefor, of a 15 radial arm mounted to swing therearound; a vertical rotary shaft at the outer end of said radial arm, and terminating in an upper angularly swinging axis arm; a rotary hollow shaft encompassing said vertical shaft; 20 a rotary earth globe on said axis arm; rotating means between said hollow shaft; and said earth globe; a sleeve encompassing said hollow shaft; a flat support fixed to said sleeve; an internal gear, rotatably mounted on said flat support, eccentrically of said vertical shaft, and carrying a moon globe supporting arm; a moon globe carried by the latter; a pinion on said hollow shaft, meshing with said internal gear, 25 causing said moon globe to revolve around said earth globe in an eccentric orbit; a fixed gear on the bottom of said flat support, concentric with said internal gear; a semi-globular phase indicator shell mounted to slid- 30 ingly rotate around said moon globe; rotary driving means between said phase indicator shell and said fixed gear; and means for rotating said vertical shaft and its encompassing hollow shaft, during the swing of said 35 40 radial arm around said sun globe, causing the respective functioning of said earth globe, moon globe, and phase indicator shell, substantially as described.

7. In a planetarium, the combination with a sun globe and a support therefor, of a 45 radial arm mounted to swing therearound; a rotary vertical shaft at the outer end of said radial arm and terminating in an upper angularly swinging axis arm; a rotary hollow 50 shaft surrounding said vertical shaft; a rotary hub freely encompassing the bottom of said axis arm, said hub being provided with a pintle element; driving means between said hollow shaft and hub; a sleeve encompassing the upper end of said axis arm, provided with an inwardly projecting curved 55 supporting member; an earth globe carried by said hub pintle at its lower portion and rotatably mounted on said sleeve at its upper 60 portion; a loose collar surrounding said pintle; a "line of illumination" band encircling said earth globe, supported at its lower portion by said collar and at its upper portion pivotally connected to said curved supporting 65 member; a moon globe mounted to swing

around said earth globe and means for revolving the same therearound; and means for rotating said vertical shaft and its encompassing hollow shaft, during the swing of said radial arm around the sun globe, substantially as described. 70

8. In a planetarium, the combination with a sun globe and a support therefor, of a radius vector arm mounted to swing therearound; a reciprocating support operative 75 radially of the outer end of said vector arm; a rotary vertical shaft, carried by said reciprocating support and terminating in an upper angularly swinging axis arm; an earth globe rotatably mounted on said axis arm; a moon 80 globe bodily carried by said reciprocating support and mounted to swing eccentrically around said earth globe; actuating means for rotating said vertical shaft, rotating said earth globe on its axis arm, and swinging 85 said moon globe therearound; and co-operating means for actuating said reciprocating support one full stroke in opposite radial directions along said vector arm during its swing around said sun globe, substantially 90 as described.

9. In a planetarium, the combination with a sun globe and a support therefor, of a radius vector arm mounted to swing therearound; a reciprocating support operative radially 95 of the outer end of said vector arm; a rotary vertical shaft, carried by said reciprocating support and terminating in an upper angularly swinging axis arm; an earth globe rotatably mounted on said axis arm; a moon 100 globe bodily carried by said reciprocating support and mounted to swing eccentrically around said earth globe; a semi-globular phase indicator shell mounted to slidably rotate around said moon globe; differential 105 means driven from said rotary vertical shaft, for rotating said earth globe, revolving said moon globe therearound, and rotating said phase indicator around said moon globe; and co-operating means for rotating said vertical 110 shaft and actuating said reciprocating support, one full stroke in opposite radial directions along said vector arm, by and during the swing of said vector arm around said sun globe, substantially as described. 115

10. In a planetarium, the combination with a sun globe and a support therefor having an offset bearing element, of a radius vector arm mounted to swing therearound; a Venus and a Mars globe mounted to swing 120 around said sun globe support, with associated means for operating the same by the swing of said vector arm; a reciprocating support operative radially of the outer end of said vector arm, intermediate of the orbits 125 of said Venus and Mars globes; an earth globe and a moon globe bodily carried by said reciprocating support and functioning substantially as set forth; a semi-globular phase indicator shell mounted to slidably 130

rotate around said moon globe; actuating means for said earth globe, moon globe, and phase indicator; a "line of illumination" indicator band mounted to encircle said earth globe and be maintained in a constant vertical position, regardless of the motions of said earth globe; a pivotal sleeve encompassing said offset bearing; a main drive shaft rotatably connected at its inner and outer ends, respectively, to said pivotal

sleeve and said reciprocating support; means operatively connecting said main drive shaft with said actuating means for said earth globe, moon globe, and phase indicator; and means for rotating said drive shaft by the swing of said vector arm, substantially as described.

In testimony whereof, I affix my signature.

ANDREW J. BAKER.
